UNITED STATES PATENT OFFICE.

HENRY H. WILLCOX, OF NEWTONVILLE, MASSACHUSETTS.

UNDERGARMENT.

1,283,006.

Specification of Letters Patent. Patented Oct. 29, 1918.

Application filed March 25, 1918. Serial No. 224,409.

To all whom it may concern:

Be it known that I, HENRY H. WILLCOX, a citizen of the United States, residing at Newtonville, county of Middlesex, State of 5 Massachusetts, have invented an Improvement in Undergarments, of which the following description, in connection with the accompanying drawing, is a specification, like characters on the drawing representing 10 like parts.

This invention relates to undergarments having provision for receiving and supporting the male genital organs, and it has for its object to provide a novel construction 15 which is comfortable to wear, and which is easily adjusted to fit the wearer in case the garment stretches or shrinks and which has more advantages, all as will be more fully hereinafter set forth.

20 In order to give an understanding of my invention, I have illustrated in the drawings a selected embodiment thereof which will now be described after which the novel features will be pointed out in the appended 25 claims.

Figure 1 is a back side view of a union suit embodying my improvement, a portion of the back side of the suit being broken out to better show the location and construction 30 of the genital-receiving and supporting means;

Fig. 2 is a fragmentary view similar to Fig. 1 showing a different form of the invention;

35 Fig. 3 is an enlarged sectional view on the line 3—3, Fig. 1;

Fig. 4 is an enlarged view of the shield member detached.

40 I have illustrated herein the invention as it might be applied to a union suit, but the invention is equally applicable to under drawers.

45 In Fig. 1, 1 indicates a union suit having any suitable or usual construction and which is provided with a front opening 2 extending from the neck to the crotch, said opening being closed by suitable buttons 3, as usual in union suits. The garment is also provided with a posterior opening which is 50 adapted to be closed by two overlapping flap members 4.

The construction thus far described is or may be all as usual in union suits and forms no part of my present invention.

55 In accordance with my invention I pro-

vide a shield member which is secured to the front of the garment at the crotch and which is centrally divided to form two sections that are detachably fastened together at their meeting edges, both at the top of the 60 shield and at the bottom thereof. This divided shield member is secured to the front of the garment so as to form with the garment front a pocket to receive the male genital organs. 65

As stated above, the meeting edges of the two parts of the shield member are detachably secured together both at the top and the bottom, the space between the upper and lower fastenings permitting an opening 70 through which the genital organs may enter the pocket. This shield member is shown generally at 5 and it is divided centrally, as shown at 10, thereby to provide the two sections 6 and 7. In the construction shown in 75 Figs. 1, 3 and 4, the shield member is shaped to present the rounded or semi-circular lower edge 8 and the straight upper edge 9. The central division line 10 does not extend clear to the bottom of the shield, but 80 terminates at the point 11 adjacent the bottom. At the lower edge, the shield is formed with a piece 12 which is separate from the two sections 6 and 7 but is sewed thereto along the line 13. The portion 12 is illustrated as being of double thickness. 85

The shield member thus made and which is illustrated separately in Fig. 4 is sewed to the front of the garment at its side and bottom edges, as indicated at 17, said shield 90 being positioned on the garment so that the lower edge of the division line 10 comes about opposite the lower end of the opening 2 and the portion 12 of the shield will fit into and be secured to the crotch portion 18 95 of the garment. The shield thus forms with the front of the garment a pocket 19 adapted to receive the genitals.

The upper portion of the meeting edges of the sections 6 and 7 are detachably secured 100 together by means of suitable separable fasteners. I have shown herein a plurality of buttons 14 which are sewed to the sections 7 and are buttoned into buttonholes in the section 6. The lower portion of the meeting 105 edges 10 are secured together by some suitable means such as loops or lacings 15.

The buttons 10 and lacing 15 are separated somewhat from each other so that at the central portion of the division line 10, the meet- 110

ing edges are not connected together. This permits the formation of a genitals-receiving opening 16.

When the garment is put on the buttons 14 will be unbuttoned, thus separating the sections 6 and 7 of the shield above the lacing. After the garment is on the genitals will be placed in the pocket 19 and the upper edges of the sections 6 and 7 will be buttoned together above the genitals, the space or opening 16 between the buttons and the lacing affording plenty of room for the genitals to enter the pocket. If it is found that the lower edge of the opening 16 is so high as to cause any discomfort, then the lacing 15 may be loosened so as to extend the opening downward. On the other hand, if it is found that the upper edge of the opening is so low as to cause discomfort, then the lower button 14 may be unbuttoned, thus extending the opening upward. By the provision of the buttons and the lacing, the opening 16 may be readily adjusted so that it will properly fit the wearer, and this opening can also be changed in case the garment shrinks or stretches as it is used so that the garment may be comfortably worn at all times.

When the garment is properly adjusted the genitals are separated from the body or leg of the wearer by the shield and thus any annoyance due to chafing caused by sweating or otherwise is entirely avoided. Further, the device performs the function of a suspensory in giving support to the scrotum.

In Figs. 1 and 4 the shield is provided with the straight upper edge 9 which is not sewed to the garment so that the pocket 19 is open at the top. In Fig. 2 I have shown an embodiment wherein the shield is elliptical in shape and is sewed to the garment throughout its entire periphery. In other respects the device shown in Fig. 2 is the

same as that shown in Figs. 1 and 3. In Fig. 2, however, the pocket will be closed at the top instead of open.

I claim:

1. An undergarment open in the front from the crotch up and having a centrally-divided shield member sewed to the front with the division line of said member in line with the front opening of the garment, said shield member having means to detachably fasten the meeting edges thereof together at the top and bottom whereby the meeting edges of said shield may be fastened together around the genitals and the space between said shield and the front of the garment constitutes a genitals-receiving pocket.

2. An undergarment open in the front from the crotch up and having a centrally-divided shield member sewed to the front with the division line of said member in line with the front opening of the garment, the meeting edges at the lower portion of said division line being laced together and those at the upper portion being buttoned together, the buttons being separated from the lacing thereby to leave an opening through which the genitals may enter the pocket formed between the shield and the front of the garment.

3. An undergarment open at the front from the crotch up and having sewed to the front thereof at and immediately above the crotch a shield member which is divided centrally in a vertical direction and which forms with the front of the garment the genitals-receiving pocket, the division in the shield affording an opening through which the genitals may enter the pocket.

In testimony whereof, I have signed my name to this specification.

H. H. WILLCOX.
